US00D938844S

(12) **United States Design Patent** (10) **Patent No.:** **US D938,844 S**
Augustine (45) **Date of Patent:** **** Dec. 21, 2021**

(54) **COMBINATION SCALE DEVICE**4,969,112 A * 11/1990 Castle G01G 19/025
177/136(71) Applicant: **Siju Augustine**, Mineola, NY (US)

(Continued)

(72) Inventor: **Siju Augustine**, Mineola, NY (US)

FOREIGN PATENT DOCUMENTS

(***) Term: **15 Years**CN 304227347 * 9/2016
CN 304269854 * 3/2017(21) Appl. No.: **29/747,340**

(Continued)

(22) Filed: **Aug. 21, 2020**

FIG. 1 is a perspective view of the combination scale device of the present invention.

FIG. 2 is a top perspective view of the combination scale device of the present invention.

FIG. 3 is a right side elevational view of the combination scale device of the present invention.

FIG. 4 is a left side elevational view of the combination scale device of the present invention.

FIG. 5. is a front elevational view of the combination scale device of the present invention; and,

(Continued)

FIG. 6 is a rear elevational view of the combination scale device of the present invention.

1 Claim, 4 Drawing Sheets
